Carpenter ATTORNEY

UNITED STATES PATENT OFFICE.

NICHOLAS LOESEL, OF RICHMOND HILL, NEW YORK, ASSIGNOR TO AMERICAN CAN COMPANY, OF NEW YORK, N. Y., A CORPORATION OF NEW JERSEY.

TALCUM-POWDER BOX WITH REINFORCED BEAD.

Application filed June 27, 1922. Serial No. 571,254.

To all whom it may concern:

Be it known that I, NICHOLAS LOESEL, a citizen of the United States, residing in Richmond Hill, Long Island, in the county 5 of Queens and State of New York, have invented a new and useful Improvement in Talcum-Powder Boxes with Reinforced Beads, of which the following is a specification.

- 10 My invention relates to cans adapted for the packaging of talcum powder and the like and has for a principal object the provision of reinforcing means for strengthening the cover-receiving part of the body. 15 Cans of this character are frequently formed with oval shape and provided with a strengthening bead in the upper part of the body, a slip cover being adapted to fit upon the portion of the body above said 20 bead. Side pressure applied in handling the cans sometimes results in crushing the can beneath the bead and this, when a bead of usual form and strength is employed, is likely to cause distortion of the body material thereabove, so that the tight frictional fit of the cover upon the body is broken and the powder permitted to escape.

My invention contemplates the prevention of this result by the provision of an extra 30 heavy bead part at the sides of the can, reinforcing the normal bead so that crushing of the sides does not seriously affect the cover-receiving part of the body.

Other objects and advantages of the invention will be apparent as it is better understood from the following description, which, taken in connection with the accompanying drawings, discloses a preferred embodiment thereof.

- 40 Referring to the drawings,

Figure 1 is a side elevation of a talcum powder can in which my invention is embodied;

Fig. 2 is an end elevation thereof with 45 certain parts shown in section; and

Fig. 3 is a sectional view taken substantially on the line 3—3 in Fig. 2.

The embodiment of the invention illustrated in the drawings comprises primarily 50 a body 11, which is of oval shape and has a strengthening bead 12 in the upper part thereof, and a slip cover, or breast 13 adapt-

ed to frictionally engage the upper part of the body above the bead 12 and provided with the usual apertured nozzle, or sifter 55 top 14. The bead 12 serves to strengthen the upper part of the can body and also limits the downward movement of the breast, the flanges of which engage the part 15 above said bead.

In order to prevent leaking of the contents, it is desirable that the close frictional contact between the side part 15 and the cover flanges be maintained. In the event that the oval body beneath the bead 12 is 60 distorted through side pressure, the ordinary bead is not sufficient to prevent slight distortion in the cross-section of the body part 15 and when this occurs, the close frictional engagement with the cover flange is interrupted and leakage of the powder results.

For the purpose of causing the part 15 to remain intact and always in condition to receive and tightly engage the cover 13, I provide supplemental reinforcing beads 16 in 65 the medium portions of the opposite side faces of the can. These parts 16 are or may be, in fact, mere continuations, or enlargements of the bead 12, and are of any desired 70 size. This improvement may, of course, constitute any deformation of the body material adjacent the bead 12 of such character as to reinforce the latter. In the present instance, the supplemental parts 16 are provided only at the sides of the can and not 75 continuously around the bead 12, this having been found sufficient to effectively maintain the body part 15 in its original form, even though the body beneath said bead be quite badly crushed. It is obvious, however, 80 that such reinforcement might be provided at any desired place and extended either partially or continuously around the encircling bead 12.

It is thought that the invention and many 95 of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely 100 a preferred embodiment thereof.

I claim:

A can for talcum powder and the like, having a body provided near its top with an outstanding peripheral bead, and a breast fitted closely around the body above said bead to form a tight joint with the body, said body being formed with reinforcements

of said bead at the median portions of its opposite sides, to preserve the shape of the upper end of the body and maintain the tightness of said joint and prevent the waste of powder when the sides of the body are bent inwards.

10

NICHOLAS LOESEL.
